Primary Examiner — Michelle E. Wilson*(74) Attorney, Agent, or Firm* — Cantor Colburn LLP(57) **CLAIM**

The ornamental design for an shelf for clothes dryer, as shown and described.

DESCRIPTION

FIG. 1 is the front perspective view of a shelf for clothes dryer showing our new design;

FIG. 2 is the front view thereof;

FIG. 3 is the rear view thereof;

FIG. 4 is the left-side view thereof;

FIG. 5 is the right-side view thereof;

FIG. 6 is the top view thereof;

FIG. 7 is the bottom view thereof; and,

FIG. 8 is the front perspective view thereof shown in an example environment.

The broken lines illustrating portions of the shelf for clothes dryer or the clothes dryer form no part of the claimed design.

1 Claim, 6 Drawing Sheets(56)
